CLAIM

The ornamental design for a steamer, as shown and described.

DESCRIPTION

FIG. 1 is a top, front, right side, perspective view of a steamer;

FIG. 2 is a front elevation view, the rear view being a mirror image thereof;

FIG. 3 is a left side elevation view, the right side view being a mirror image thereof;

FIG. 4 is a top plan view thereof;

FIG. 5 is a bottom plan view thereof;

FIG. 6 is a cross-section view thereof taken along line 6-6 of FIG. 3;

FIG. 7 is an exploded perspective view of the device of FIG. 1, including a pot and lid as environmental matter; and,

FIG. 8 is an exploded perspective view of the device of FIG. 1, including a Dutch oven and lid as environmental matter. In the drawings, the broken lines are for the purpose of illustrating environment only and form no part of the claimed design.

1 Claim, 8 Drawing Sheets
